CONTINUOUS PROCESSES FOR SOLVENT EXTRACTION OF OIL FROM OIL-BEARING MATERIALS AND REFINEMENT OF THE RESIDUAL SOLID PRODUCT

Michele Bonotto, Princeton, N. J.

Application July 23, 1945, Serial No. 606,638

4 Claims. (Cl. 260—412.8)

1

This invention relates to improvements in continuous processes for solvent extraction of oil from oil-bearing materials and refinement of the residual solid product.

One of the objects of this invention is to provide a process and apparatus in which oil-bearing material is in a continuous process extracted by a liquid solvent in an extractor at relatively low extracting temperatures, and preferably with liquid gasoline having a boiling range between 147° F. and 205° F.; the extracted solid product is then fed directly from the extractor into a solvent eliminator known in this art as a "direct dryer" and is there preheated by solvent vapors, preferably obtained by superheating the used solvent vapors from the system, to a temperature above the condensation temperature of steam, whereupon such preheated material is subjected to refining and final elimination of solvent by blown steam either in a section of the same "direct dryer" used to blow said solvent vapor or in a separate similar apparatus.

My invention thus results in eliminating the conventional step, and the extensive apparatus employed therein, of initially preheating and pre-drying such material by indirectly applied heat or through the use of intermediate heat-transferring surfaces.

Another object of my invention is to speed up and greatly reduce the time required to process or refine solvent-extracted oil-bearing material and furthermore to refine a solid protein product of better quality from which the oil and solvent will be completely eliminated and in which the proteins will be maintained in undenatured and uninjured condition without loss of the natural moisture content.

In continuous extraction systems of the prior art, the use of heaters of indirect type has heretofore always been considered necessary for the purpose of elevating the temperature of solvent-extracted products, so as to preheat the same from the relatively low temperature at which they leave the solvent-extraction apparatus, to the relatively high temperature of 200° F. or 212° F. necessary to control or avoid condensation of steam in solvent eliminators or direct steam dryers.

During preheating treatment in an indirect dryer of the conventional type, the extracted meal is conveyed in a series of long horizontally-disposed steam-jacketed tanks for a considerable time period and subjected to agitation by the conveyor devices or to a lifting and tumbling operation as well as to indirectly-applied heat in order

2

to eliminate part of the solvent while the material is being moved forwardly in such devices. During this movement part of the natural moisture contained in the extracted meal is also evaporated with the solvent and passes off with the solvent vapor while the temperature of the material rises due to the heat transmitted through the jacketed walls of the apparatus.

It has been found that such agitation, lifting, or tumbling operation, as well as the reducing of the natural moisture of the solvent extracted material, produces conditions which are favorable to the creation or production of a fine dust, and this dust is carried by the solvent vapors to the condensers where a fouling or scaling of the condenser surfaces occurs. Such a fouling or scaling obviously reduces the efficiency of the condensers and frequent periodic cleanings are necessary. Such cleanings constitute an appreciable slowing up and nuisance factor especially in systems which are designed to run continuously.

It has been found, furthermore, that in handling certain oil-bearing materials, such as extracted flaxseed and cotton-seed, a very high percentage of dust is created and a part of this dust is of such fineness that it is carried out of the condensers with the condensate, thus creating difficulties in the solvent storage tanks where such dust accumulates, and heretofore, in order to avoid or partially take care of the above deleterious conditions, it has been the practice to interpose between the vapor-outlet of the indirect dryer and the condenser one or more dust collectors of the conventional type. These dust collectors usually comprise a jacketed expansion-chamber followed by a water-spraying chamber where the dust is collected and carried out with the water which is sprayed in fine subdivision at a temperature above the boiling point of the solvent so as to avoid condensation of the same. Notwithstanding the above, some solvent and some material in dust form are always lost in the operation of these dust collectors.

By the use of my present invention, the step in the system of employing indirect dryers for driving out part of the solvent with indirect heat and also initially preheating the material is completely eliminated with the result that the use of such indirect drying apparatus with all the disadvantages hereinabove specified is avoided, and also all the accessories used therewith, such as motors, drives, conveyors, dust collectors, etc. are also eliminated with the accompanying economy of apparatus, space and expense.

While it is well known in this art that whenever conditions permit, it is more economic to transmit heat directly to the material instead of indirectly, in conventional prior art systems, the final elimination of solvent from the extracted material is necessarily accomplished by steam as the heating or distilling element, and it has heretofore been impossible to follow the above-mentioned economic principle by the use of a total application of direct heat for steam-distilling and solvent-eliminating because of the fact that the heated mass of extracted material leaves the extractor at temperatures well below 212° F., and if such mass were immediately introduced into a direct steam dryer, the condensation of such direct steam in the mass would create serious difficulties which vary somewhat according to the type and quality of material under direct steam treatment. For example, solvent-extracted flax-seed will, under such direct steam treatment, agglutinate in a mass of the consistency of a poultice, and this will absolutely prevent the handling of such material by direct steam treatment.

Another object of my invention is to economize the steam conventionally used in the process and apparatus for drying and preheating solvent-extracted material through indirectly-applied heat, and to substitute therefor a process and apparatus which not only avoids the difficulties and disadvantages inherent in the use of such prior process and apparatus but produces a product of better quality.

With these and other objects the invention comprises the steps in the method and the combination and arrangement of apparatus so combined as to co-act and cooperate with each other in the performance of the functions and the accomplishment of the results herein contemplated, and comprises in one of its adaptations the species or preferred form illustrated in the accompanying drawing.

The figure of the drawing is a diagrammatic view embodying a preferred form of apparatus for carrying out a preferred embodiment of my process.

Referring now to the accompanying drawing in accordance with the preferred form of my invention, I feed oil-bearing material which may comprise the meal of a suitable oil-bearing seed or fish-scrap from a conventional hopper 1 and pass the same through a solvent-extraction column 2 preferably of the type shown and described in my patents numbered 2,158,782 or 2,206,595. In this extractor 2, a liquid solvent usually comprising gasoline with a boiling range between 147° to 205° F. is obtained from a solvent storage tank 5 and is heated to a degree below its boiling point by heater 3 and pumped by pump 4 through the mass in counter-current to the passage thereof, whereupon the extracted product leaves the extraction column at approximately 145° F. It is now necessary to eliminate the solvent and the final traces of such solvent from this extracted product, and to accomplish this result with the least possible injury to the proteids and without denaturation thereof. This is most advantageously and economically accomplished by subjecting the extracted product to blown superheated steam in a direct steam dryer of the type shown and described in my former U. S. patents numbered 2,191,255 and 2,277,361, but before this step can be accomplished the temperature of said extracted product must be elevated to a point approximating or above the condensation temperature of the steam used in order to avoid the difficulties hereinabove speci-

fied, and, as aforesaid, this has been heretofore done in two steps, first, by the use of indirect dryers which resulted in injury to the product by the agitating, conveying or lifting and tumbling as well as the increased time period to which such material is subjected to heat and with the other disadvantages and difficulties also specified above, and second, by the subjection of the material to the solvent-eliminating action of steam directly blown into the mass in a direct dryer.

In accordance with my present invention, I immediately in a continuous process subject the extracted material to the temperature-elevating step of blowing solvent vapors directly into the mass at a temperature above the condensation point of steam. For this purpose, I connect directly the extractor 2 by a simple conductor 2^a with a vapor-blowing apparatus 7 and utilize in a section 7^a provided therefor in the said vapor-blowing apparatus or direct dryer tank 7 a part of the vapors of an oil-extracting solvent, and preferably the superheated vapors of the solvent which has theretofore been used in the extractor 2. Such solvent vapors may be produced in an apparatus specially provided for the purpose such as the solvent vaporizer 8, but, in the preferred form of my invention, these vapors are taken from a suitable section of the conventional distilling apparatus in which the micella is treated to recover the oil. As shown, the micella is conducted from the extraction column 2 by conduit 2^b to a micella tank 9 and thence conducted through various apparatus to a calandria 16 and expansion chamber 17 from which part of the vapors are passed through the blower-compressor 18 and conduit 19 to a vapor-superheater 20 and thence to the direct-dryer tank 7. As shown, the micella is conducted by conduit 9^a to pump 10, which pumps the micella through conduit 10^a, thence through rotameter 11 and conduit 11^a to a condenser 12 in which part of the liquid solvent contained in the micella is preheated. The micella is then conducted through conduit 14, heater 15 to the calandria 16 and vapor chamber 17, which is also connected by the conduit 13 with the condenser 12 in which part of the solvent vapors is used as a heating medium. If necessary, the solvent vapors may be all conducted to the superheater 20, where after suitable superheating, they are conducted and blown, as aforesaid, into the said section 7^a of the direct dryer tank 7. In this section 7^a the protein product is heated directly by the vaporized solvent and brought to a heat of approximately 210°-220° F. In utilizing these vapors I preferably, by the use of the superheater 20 placed before the solvent vapors enter the dryer, raise the temperature thereof, according to chemical and physical characteristics of the solvent, to approximately 230° to 240° F. These vapors at this relatively high temperature are, as stated, injected directly into the product through a set or series of lower nozzles 1^b. The nozzles are of the type shown at 4^b in my Patent #2,199,255. The use of these superheated vapors in direct contact with the extracted material, which, as hereinabove stated, is passed from the extractor at approximately 140° will cause said temperature of the extracted material to be elevated or raised to approximately 210° F. which comprises a mass or product temperature that is necessary to permit a subsequent direct steam treatment, and in the preferred embodiment of my invention, I utilize in the same direct-dryer tank 7 a steam-drying and solvent eliminating section 7^c produced by a series of nozzles 7^c positioned at a higher level of the material.

and I preferably inject superheated steam through said set or series of nozzles directly into the material in the tank 7. This tank 7 preferably is constructed substantially as shown in my Patent #2,199,255 except as herein specified. When solvent vapors for use in my dryer are taken from the vaporizing portion of the distilling apparatus where the micella is treated to recover the oil, a substantial economy will result because the heat utilized to elevate or raise the temperature of the mass or product would otherwise pass into the water of the condensers. When so utilizing such vapors and steam in a common direct-dryer these vapors will rise in the material and will then join and commingle with the superheated steam and pass off to a conventional condenser 21. In the system shown, the separated oil passes from the vaporizer chamber 17 through conduit 22 and heater 23 to a stripper column 24, whereupon the last traces of solvent are vaporized and pass with the steam which is injected at the lower end of the column through conduit 25 to the condenser 26 and, as shown, both condensers 21 and 26 are connected to a water separator 27 from which the solvent may be conducted by conduit 28 to the pure solvent storage tank 5.

It will be understood that by the use of solvent vapors from the micella treating section of the system, applicant avoids the necessity of independently vaporizing solvent to procure these vapors and this results in very considerable economy in the system.

In case no micella is under distillation, I may conduct by suitably valved conductor 29 pure solvent from the solvent-storage tank 5 to the pre-heater 15 and calandria 16 where it is vaporized and then passes through the expansion chamber 17, blower-compressor 18 and conduit 19 to the preheater 20, nozzles 7^a and into the product in the tank 7.

The words "direct-dryer" as used herein are intended to refer to apparatus in which the liquid solvent that is still contained in the extracted material is removed in vapor form by direct application of steam to the mass.

It will be understood that any part of the solvent vapors that may be condensed in the solid residual mass will be eliminated together with the original liquid solvent by the blowing of the steam therethrough.

Having described my invention, I claim:

1. The process of solvent extraction and refining of vegetable and animal substances consisting in subjecting the raw material to oil extraction with a liquid solvent having a boiling point less than the condensation point of steam by continuously moving the raw material through an extraction column and causing the temperature of the residual meal product to be lower than the condensation temperature of steam, feeding the residual product in an operation continuous with said extraction from the lower end of said extraction column into a direct-dryer, elevating the temperature of the meal product to a point approximating the condensation temperature of steam by blowing vapors of a solvent similar to that employed in the subjection of material to

oil extraction heated to a temperature above the condensation point of steam directly into said residual product in such continuous operation to bring said product to a temperature approximating said steam condensation point, and then blowing steam directly into said vapor-heated product to eliminate by steam distillation the solvent therefrom.

2. The process claimed in claim 1 in which the residual material is moved in an upward direction in an upright direct-dryer, solvent vapor is blown into said residual material at one level, the steam is blown at a higher level than the solvent vapors and both vapor and steam move together in the same direction as the residual material.

3. The process of solvent extraction and refining of vegetable and animal substances consisting in subjecting the raw material to oil extraction with a liquid solvent having a boiling point less than the condensation point of steam by continuously moving the raw material through an extraction column and causing the temperature of the residual meal product to be lower than the condensation temperature of steam, feeding said residual material in an operation continuous with said extraction directly from the lower end of said extraction column to an upright direct-dryer and moving said material therein in a substantially vertical direction, elevating the temperature of the meal product to a point approximating the condensation temperature of steam by blowing at a level above the feeding inlet vapors of a solvent distilled from micella obtained in the extraction step, heated to a temperature above the condensation point of steam directly into said residual product to bring said product in such continuous operation to a temperature approximating said steam condensation point, and then blowing, directly into said vapor-heated product at a level of the moving material higher than that at which said vapor is blown, steam to eliminate by steam distillation the solvent therefrom and to cause discharging movements by buoyancy of both vapor and steam in the direction of movement of the material.

4. The process as claimed in claim 3 in which the directly blown solvent vapors are heated to approximately 240° F. and the residual process product is heated to approximately 212° F. prior to subjecting the same to blown steam.
